No. 813,957.

PATENTED FEB. 27, 1906.

H. W. EISENHART.

H. W. BIGELOW,
GRAIN THRESHING AND SEPARATING MACHINE.

APPLICATION FILED JUNE 20, 1905.

9 SHEETS—SHEET 1.

<img alt="Technical drawing of a mechanical device, labeled Fig. 1, showing a vertical assembly with various components labeled 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 517, 518, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 617, 618, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 717, 718, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 817, 818, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 917, 918, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1017, 1018, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1117, 1118, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1217, 1218, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1317, 1318, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1417, 1418, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1517, 1518, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1617, 1618, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1717, 1718, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1817, 1818, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1917, 1918, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, UNITED STATES PATENT OFFICE.

HENRY WOLF EISENHART, OF YORK, PENNSYLVANIA, ASSIGNOR TO
A. B. FARQUHAR COMPANY, LIMITED, OF YORK, PENNSYLVANIA.

GRAIN THRESHING AND SEPARATING MACHINE.

No. 813,957.

Specification of Letters Patent.

Patented Feb. 27, 1906.

Application filed June 20, 1905. Serial No. 266,137.

To all whom it may concern:

Be it known that I, HENRY WOLF EISENHART, a citizen of the United States, residing at York, county of York, and State of Pennsylvania, have invented a new and useful Improvement in Grain Threshing and Separating Machines, of which the following is a specification.

My invention has for its object to improve grain threshing and separating machines, and is especially designed for use in machines that are to be operated in the southwestern portions of the United States and in Mexico, where the climatic conditions are peculiar and where the character of the grain to be threshed is different from that usually found in more northern latitudes. To meet the climatic conditions, I have devised the framework of the machine with especial reference to withstanding extreme variations of moisture and dryness, as well as to withstand long-continued and rough usage. The grain raised in the regions referred to is often weedy, and the heads of the wheat or other grain contain a relatively large proportion of imperfectly-developed kernels. The seeds of the weeds or foreign growths and the inferior kernels of the grain should be separated from the perfect kernels and should then be separated from the chaff and straw, as they can be utilized for various purposes, such as feed for fowls.

My invention has for one of its objects to produce a machine especially adapted for operating upon grain of the character referred to. In the drawings, wherein the preferred form of my invention is illustrated, Figure 1 is a side elevation of the complete machine. Fig. 2 is a central longitudinal section of the same. Figs. 3 and 4 are detail perspective views of curtains or deflectors arranged within the machine and which will be later described. Fig. 5 is a side elevation, drawn on a much larger scale than Figs. 1 and 2, showing the front end of the machine. Fig. 6 is a vertical longitudinal section of the parts of the machine shown in Fig. 5. Fig. 7 is a front end view of the machine. Fig. 8 is a perspective view of the rear end of the feeder. Fig. 9 is a perspective view of the detachable side plate that is secured to the side wall of the hood at the feed end of the machine opposite the end of the feeder. Fig. 10 is a perspective view of the several parts which together constitute the housing at the feed end

of the machine, the parts being separated from each other for purposes of illustration. Fig. 11 is a perspective view, detached, of the reel or beater employed in front of the threshing-cylinder. Fig. 12 is a perspective view, enlarged, illustrating part of the supports for the concave, the adjusting means therefor, and of the parts in immediate juxtaposition. Fig. 13 is a perspective view of a portion of the shaking-screen, illustrating means for guiding and steadyng the same in the frame. Fig. 14 is a perspective view, detached, of one of the guiding and steadyng rollers for the shaking-screen. Fig. 15 is a perspective view as seen from the rear of the separator for the foul seed and inferior grain. Fig. 16 is a longitudinal sectional view of the separator shown in Fig. 15, illustrating also its relation to the main threshing-machine. Figs. 17 and 18 are perspective views of different portions of the bottom of the separator shown in Figs. 15 and 16.

Referring to the drawings, 1 designates the main framework or casing of the machine; 2, the supporting-wheels; 3, the threshing-cylinder; 4, the concave opposite thereto; 5, the shaking-screen and straw-carrier that receives the threshed straw from the cylinder and after operating thereupon to separate the grain delivers it at the tail end of the screen, and 7 the shaking-shoe containing the screens wherein the grain delivered from the straw-separator 5 is cleaned by the aid of an air-blast produced by the fan 6. These parts in their general arrangement and construction are of a well-known type and need not be specifically described. The belting for driving the moving parts of the thresher is indicated in dotted lines in Figs. 1, 2, and 5; but as this may be arranged in any of several well-known ways it is not deemed necessary to describe its course or arrangement. 8 represents a frame in which the feed-belt 9 is mounted, and 10 represents the legs by which the outer end of this frame is supported, the connection between the frame and legs being of such nature as to permit the frame to be adjusted toward or from the ground, as may be desired. These parts may also be of any usual or preferred construction.

At the feed end of the machine and above and inclosing the threshing-cylinder I form a hood 11, that opens toward the front and ex-

tends upward a considerable distance above the top of the machine or main framework, so that the feed of the straw to the cylinder may be downward. I prefer that this hood 5 should be formed mostly of metal, as I have found that this part of the machine is particularly subjected to great strains and severe vibrations, and when constructed of wood it does not well withstand these 10 destructive tendencies, especially when also subjected to the severe climatic conditions of the portion of the country to which I have referred. In Fig. 10 the parts that enter into the construction of the hood 11 are represented in detail. 12 12 represent the metallic side pieces of the hood, and 13 the top supported thereupon. The side pieces are of an approximately quadrant shape, so that the front of the hood when closed in by the 15 side and top has its front end left open and is also open at the bottom to give free access to the cylinder. The side pieces 12 rest upon sills 14, to the under sides of which are bolted the side pieces 15, in or upon which are supported the bearings 16 for the threshing-cylinder and the curved arms 17, in which are 20 mounted the cross-bars 18, that carry the teeth of the concave 4. The side pieces 12 are cut away at their front edges, as indicated at 19, to allow the end of the feeder-frame 8 to be carried into the hood, as indicated in Figs. 2 and 6.

The ends of the shaft 20 of the turning roller at the upper end of the feeder extend 25 laterally beyond the side boards of the frame 8 and are mounted in plates 21, Figs. 5, 9, and 10, that are secured to the side plates 12 of the hood, so as to cover the cut-away portions 19 of the side plates. As indicated in 30 the drawings, these plates are offset from the sides 12 and are formed with slots or recesses 22, that constitute bearings or seats for the shaft 20. In order to furnish an additional bearing for the shaft to steady the same on 35 the side carrying its driving-pulley, I provide a bracket-bearing 23, Figs. 7 and 10. The arrangement that I have described permits the outer end of the feeder to be adjusted vertically without disturbing the relations of 40 the inner end thereof to the hood and the threshing mechanism contained therein. The side bearing-supporting parts 15 of the frame of the hood are each provided with a leg 24, that is adapted to rest upon and be secured to the main sill of the framework of 45 the machine.

It will be seen by reference to the drawings that the threshing-cylinder is mounted in the upper part of the casing or framework of the 50 machine, as is usual, and that the hood formed of the side pieces 12 and the top 13 stands considerably above the top of the main frame. In order to provide for the storing and transportation of the machine, 55 this hood is made removable, as indicated in

Fig. 10, so that it may be taken off, thereby materially reducing the vertical dimensions of the machine as a whole. To facilitate this removal of the hood, the connection of the feeder-frame 8 with the thresher is such as to 60 allow easy separation, the shaft or journal 20 of the feeder being mounted in open bearings carried by the said removable hood. By offsetting the plates 21, in which the bearings for the shaft 20 are formed, I am enabled to 65 use a feed-belt of the full width of the threshing-cylinder and of the hood, which is desirable in threshing unbound or loose grain.

It will be seen by reference to Fig. 6 that the feeder delivers the straw into the hood 80 considerably above and somewhat to the rear of the cylinder 3, as I have found that better results are obtained when the parts are thus arranged, particularly when operating upon tangled grain. Between the delivery end of the feeder and the threshing devices I arrange a feed-board 25. I prefer that this feed-board should be supported at its lower end upon a cross-bar 26, carried by the concave or by the arms 17, that carry the concave, and at its upper end by pins or studs 27, projecting from the side walls of the hood and extending through slots in plates 28, carried by the feed-board. The concave is adjustable toward and from the cylinder, and 85 the feed-board being loosely mounted and supported directly upon the cross-bar 26, connected with the concave, is adjustable therewith, so that under no circumstances can there be a space left between the feed-board and the threshing mechanism. The curved arms 17, that support the concave, are 90 mounted at their inner ends upon an axis 29 and near their outer ends rest upon cams 30, secured fast to the shaft 31, that is mounted 95 in the side pieces of the casing or hood 11, and to the outer end of which is connected an 100 arm 32, by which the positions of the cams, and consequently of the concave, may be varied. The arm 32 is arranged adjacent to 105 the quadrant 33, and a winged nut and threaded bolt 34 are the means employed for securing these parts in the positions to which they may be adjusted. The front end of the 110 casing below the feed-board is closed by the 115 end board or plate 35, and to the lower edge of this is secured a cross-bar 36, to the inner lower edge of which is secured a deflecting-strip 37, arranged to direct the grain which 120 may fall thereupon to the flooring of the shaking-screen and separator 5. The cross-bar 36 is removable, thereby giving access to the under part of the concave and to the forward end of the shaking-screen and separator 5 from the front. The end board 35 and the 125 bar and deflector-plate 36 and 37 not only prevent the grain from escaping at the front of the machine and deliver it to the separator, but also prevent dust from escaping.

43 43 are curtains or deflectors for the 130

grain, preferably flexible, secured to the lower edges of the sides of the hood 11 and serving to direct the grain that falls from the concave to the bottom or floor of the shaking 5 screen and separator 5.

The vertical side boards of the shaking-separator 5 are provided near their front ends with guide or rub plates 44, against which bear rollers mounted in bearings 46, secured 10 to the framework of the machine. The axes of the rollers 45 and the rub-plates 44 are preferably inclined, as indicated in Fig. 5. These parts prevent the shaker 5 from rubbing against the sides of the frame and cause 15 it to run true.

In the upper forward portion of the hood and directly above the delivery end of the feeder there is mounted a beater-cylinder 38. (Illustrated in detail in Fig. 11.) This operates to assist the feeder in delivering the straw to the thresher mechanism and prevents clogging of the machine if the straw be fed in irregular masses. The beater is preferably formed of the heads 39, the cross-bars 20 40, extending between the heads, and the teeth 41, carried by the cross-bars. The beater is driven in the direction indicated by the arrows.

In rear of the beater and depending from 25 the top of the hood is a flexible curtain 42, that prevents the straw that may be acted upon by the beater from being carried back upon the upward-moving portion of the cylinder. It serves, in conjunction with the 30 feed-board, to direct the straw to the thresher-cylinder and by reason of its being flexible and yielding adjusts itself to the conditions of the feed.

The threshed straw passing rearward from 35 the threshing-cylinder and the concave is caught by a beater 47, that operates to open and spread the straw, allowing the grain to separate therefrom, and to assist in delivering it to the screens in the frame of the shaking-separator 5.

A little in rear of the beater 47 there is suspended from the top of the casing a sectional curtain 48. (Illustrated in detail in Fig. 3.) It serves to prevent the grain and straw from 40 being thrown by the threshing-cylinder far to the rear of the machine without first being caught and acted upon by the separating-screens in the shaker 5. It sometimes happens that the stream of straw issuing from 45 the threshing-cylinder is of uneven thickness transversely, and because of this fact I prefer to make the curtain 48 of independently-movable sections, so that one part may swing backward and upward to allow a mass of straw of unusual depth to pass, while the other sections, where the passing straw is of less depth, may hang down and close the rear portion of the machine from the flying grain.

49 49 indicate the independently-hinged 55 sections of the curtain or screen 48. I have

found that it is preferable to make these independent sections only about half the vertical dimensions of the curtain as a whole. I therefore hinge or pivot each of the sections to the lower edge of a depending hinged curtain or screen section 50 of the full width of the machine and pivoted close to the top of the casing.

51 is a toothed cylinder, and 52 a toothed concave arranged opposite the cylinder, these 70 two operating to act upon the straw after it has been threshed and then separated from the grain in order to break it up or bruise it that it may be in a pliable and easily-handled condition. The cylinder is preferably over-acting, and the concave is arranged above the cylinder. A reel 53 in front of the cylinder and concave just referred to operates to feed the straw to the latter, as well as to open it up, and thereby insure that any grain 75 which may have been retained therein shall escape from the straw before it is passed to the breaking-cylinder. These parts may be of any usual or preferred construction. In rear of the cylinder just referred to is a screen 54, which is represented in detail in Fig. 4. It is held rigidly in position by stops 55, secured to the side walls of the casing, and operates to prevent the escape from the rear end of the machine of any grain which may have 80 remained in the straw and been caught and thrown rearward by the cylinder 51.

The blast from the fan 6 is so regulated that not only the chaff, but also the lighter seeds that may have been contained in the 85 mass of straw delivered to the machine, as well as the imperfectly-developed kernels of grain, are carried by the blast over the tail of the shoe 7. Heretofore there has been no provision made, so far as I am aware, for 90 cleaning such seed and imperfectly-developed grain in the threshing and separating machine. I have provided means for taking the material delivered from the shaking-shoe 7, as well as from the straw-separating shaker 95 5, and performing a secondary or supplemental cleaning, whereby the chaff and straw are separated out and carried off and all seeds of whatever nature that may be of value or in any way utilized are cleaned and saved. The 100 straw, chaff, and other light material which pass over the tail of both the shaking-shoe 7 and the shaking-separator 5 are received upon the bottom of a fore-and-aft vibratory separator-frame 57, toward which the material discharged from the upper separator 5 is directed by a transverse depending end curtain 56, Fig. 16, hinged to the top of the casing of the machine and provided with one or more straps 156, hinged at one end to the curtain 56 and formed with a series of holes, through one of which may be passed the pin by which it is made fast to the side of the casing. In this way the end curtain can be swung outward to any desired angle of inclination and 110 115 120 125 130

- be secured in that position. The frame 57 is hung by long elastic straps 58 from a supporting structure disposed at the rear of the threshing-machine and preferably connected directly thereto. To this frame 57 is imparted longitudinal reciprocatory movement from a power-driven crank 60, suitably mounted in the main frame of the thresher and connected with the shaking-frame 57 by a pitman 61. A long thin elastic metallic radius-bar 62, secured at one end to one leg of the frame 59 and at the other end to a bracket 63, attached to the rear portion of the frame 57, serves to prevent undue lateral movement of the shaking-frame. The bottom of the frame 57, upon which the straw, chaff, and relatively light grain and seeds from the shaking-shoe 7 and shaker 5 are delivered, is serrated or ribbed, as indicated in Figs. 15, 16, 17, and 18, the inclination of the serrations being such as to cause a progressive feed of the material toward the discharge end of the frame. The flooring nearer the feed or head end of the frame 58 (indicated by 64 and illustrated in detail in Fig. 17) is imperforate and acts as a feeder, the seeds, &c., separating themselves from the straw during their rearward passage over this imperforate corrugated portion, while the portion of the flooring nearer the delivery end of the frame (indicated by 65) is perforated, as represented in detail in Fig. 18, to permit the downward escape of the separated-out seeds, &c. Below the perforated portion 65 of the serrated flooring is a hopper-like chamber 66, having inclined bottom walls that lead to the trough or spout 67, through which the cleaned seed and imperfectly-developed grain are delivered. A blast from the fan 68 is delivered into the chamber 66 and, escaping therefrom through the openings in the perforated portion 65 of the flooring, blows the chaff and straw over the discharge end of the separator, but allows the seed to fall through the openings onto the floor of the chamber, whence they pass to the delivery-spout 67. The blast produced by the fan 68 will of course be regulated to suit the character of the material it is to operate upon.
- Having described my invention, what I claim, and desire to secure by Letters Patent, is—
1. The combination of a threshing-cylinder and concave, a casing or hood inclosing a space above the cylinder having side walls and a top, the side walls being cut away in front, offset plates secured to the side walls of the casing or hood opposite the cut-away parts thereof provided with bearings, and a feeder for the straw and grain to be threshed supported in the said bearings in the offset plates, substantially as set forth.
2. In a grain-threshing machine, the combination with the threshing-cylinder and concave and the straw and grain separating mechanism, of a curtain arranged in rear of the cylinder to prevent the grain thrown rearward thereby from flying out at the tail end of the machine—the curtain comprising a section, 50, hinged to the casing of the machine near its top and hanging downward therefrom, and of a width approximating the width of the machine, and a series of transversely-arranged sections, 49, independently hinged to the lower edge of the section, 50, from which they hang freely suspended, substantially as set forth.
3. The concave having its curved side arms pivoted at their rear ends to the side plates 15, and provided at their front ends with a cross-rod 26 connected to and extending between them, and the concave-adjusting devices, in combination with the feed-board 25, having its lower end resting on and engaging the cross-rod 26, and slotted plates 28 at its upper end engaging pins or studs 27 on the side walls of the frame, as and for the purposes hereinbefore shown and described.
4. The combination of the bruising-cylinder 51, and concave 52, the straw-separating shaker 5, the grain-cleaning shaking-shoe 7, the fan 6, the shaking-frame 57, arranged to receive the discharge from the shaking-shoe 7, and shaker 5, such shaking-frame having a serrated or ribbed bottom imperforate near its forward end and perforated toward the rear, means for supporting the frame 57 and imparting thereto longitudinal reciprocating movements, a collecting-chamber arranged below the perforated portion of the bottom of the frame, and a blast-fan 68 arranged to discharge into the said collecting-chamber, substantially as set forth.
- In testimony whereof I affix my signature in presence of two witnesses.
- HENRY WOLF EISENHART.
